UNITED STATES PATENT OFFICE.

FRANCIS HOGG, OF PITTSBURGH, PENNSYLVANIA.

SIGNAL DEVICE.

Application filed August 2, 1926. Serial No. 126,360.

This invention relates to signaling devices and more particularly to marine danger signals.

One of the objects of the invention is the provision of new and improved danger signal mechanism that is adapted to be automatically operated.

Another object of the invention is the provision of new and improved power generating mechanism that is adapted to be automatically operated by the movement of the supporting medium.

A still further object of the invention is the provision of a new and improved signal buoy that when in use is adapted to emit continuously intermittent sight or sound signals, or both, the mechanism being operated by the movement of the water.

Another object of the invention is the provision of a new and improved signal device that is simple in construction, efficient in operation, cheap to manufacture, easily assembled, and that is not likely to become broken or out of order.

Other and further objects and advantages of the invention will appear from the following description taken in connection with the accompanying drawings, in which

Fig. 1 is a side elevation of a buoy with the invention in position thereon.

Fig. 2 is a longitudinal vertical section of the buoy with single mechanism therein.

Fig. 3 is a wiring diagram of the signaling device.

Fig. 4 is side elevation of a modified form of the device with parts in section and parts broken away.

Referring now to the drawings on which similar reference characters designate the same part throughout the specification, the numeral 10 designates a buoy anchored in the water 11 by the cable 12 as is usual in such constructions.

The buoy comprises the casing 13 on the upper end of the cylindrical portion of which the signal mechanism 14 is mounted.

The lower end of the buoy is provided with an axial projection in the form of a journal 16 on which is rotatably mounted a sleeve 17. This sleeve is provided with an eye 18, to which is connected the upper end of the anchor cable 12.

The casing 10 is provided with a plurality

of vanes or fins 19, arranged spirally about the exterior of said casing whereby the movement of the water or other supporting element past the buoy will cause the same to rotate for operating the mechanism contained therein, as will presently appear.

In floating signals for indicating sunken vessels, concealed rocks and the like, it is desirable that signals be employed that will indicate their location in all kinds of weather and at night as well as in the day time. Light signals alone are unreliable in foggy weather and likewise sound signals alone cannot be relied on in adverse winds.

In the use of visible signals, better results are obtained by causing an intermittent flashing of the signals for the reason that intermittent light signals are more noticeable than those having a continuous light and for the further reason that the intermittent light may be made to indicate or identify the place where they are located, either by varying the order of the flashes or by the use of different colored lights flashed in a predetermined order.

It is also desirable that where sound signals be employed the same be operated intermittently for similar reasons. In both cases less energy is required to operate the signals intermittently than to maintain continuous signals.

The present invention contemplates the use of both visible and audible signals, altho it is understood that either may be employed without the other. It is desirable, however, that both be employed in order that each may supplement the other.

In the form of the device disclosed in Figs. 1 to 3, a housing 21 comprising the two sections 22 and 23 is secured in an axial opening in the closure 24 as by means of the flanges 25 and 26 on the sections 22 and 23 and the bolts or rivets 27. The section 22 is provided with an axial extension 28 of suitable length for supporting the signal devices.

A transparent cup-shaped enclosure 29 is secured on the laterally extending flange 31 of the upper end of the extension 28 in which is mounted the optical signals comprising the electric light bulbs 32. An electric horn 33 extends thru the flange 31. The horn is directed downwardly in order that any water entering the same may run

out and not interfere with the operating mechanism.

The casing 13, housing 21 and enclosure 29 are so connected that no water may enter the same.

Suitable means are provided for operating the signal devices. In the form shown to illustrate one embodiment of the invention, a generator 34, storage battery 35 and switch mechanism 36, are employed for energizing and controlling the signals. The parts are so arranged that the rotation of the casing 13 by the waves or tides, or both, will operate the generator.

15 A receptacle 37 thru which extends a tubular member or journal 38 is mounted within the housing 21. The receptacle 37 is preferably cylindrical and the tubular journal 38 extends axially thru the same and has its 20 ends extending above and below the said receptacle.

The lower section 23 of the housing 21 is provided with downwardly extending sleeve bearing 39 thru which the tubular journal 38 25 extends.

The upper end of the sleeve bearing 39 is provided with an enlargement 41 for receiving thrust bearings 42 carried by said journal 38 and sleeve 39.

30 The lower portion of the section 23 of the housing 21 is provided with a depression 43 across which the bearing plate 44 is secured. The bearing plate 44 is provided with a depression 45 across which extends 35 a flanged portion of a spacer 46. The spacer 46 is preferably secured to the receptacle 35 and keyed to the tubular journal 38. Antifriction bearings 47 mounted in the depression 45 are employed for assisting 40 in supporting the housing 21.

A suitable generator 34 of any approved construction is secured on the lower projecting end 48 of the tubular journal 38, in any suitable manner, as by means of clamp 48 rigidly secured to said generator. Suitable antifriction bearings 51 are interposed between the lower end of the sleeve 39 and the journal 38.

The sleeve 39 is provided with gear 52, 50 which is in mesh with pinion 53 on the armature shaft 54 of the generator 34.

In the use of the device the buoy is anchored in the usual manner and the movement of the water, such as waves or tides 55 passing the buoy will cause the same to rotate, thereby rotating the gear 52.

The tubular member 38 will be held from rotating by the weight of the generator which is rigidly attached thereto. Since 60 the weight of the battery 35 will be greater than the control mechanism 36, the battery 35 will assist in holding the member 38 from rotating since the receptacle 37 is rigidly mounted on said member. The rotation of 65 the gear 52 will operate the generator thru

the pinion 53 to generate electricity in the usual manner.

The leads 55 and 56 from the generator are carried upward thru the stationary tubular journal 38, thru suitable opening in said 70 journal to the terminals 57 and 58 of the battery.

The upper end of the tubular member 38 is provided with collecting rings 59 and 61, which are adapted to be engaged by suitable brushes 62 and 63, carried by the housing 21.

Conductors 64 and 65 are provided for connecting the brushes 62 and 63, respectively, with the electric light bulbs 32 and 80 the horn 33. The bulbs and horn preferably being connected in multiple, as shown clearly in Fig. 3.

If it is desired that the signal devices operate continuously, the terminals 57 and 85 58 of the battery are connected to the collecting rings 59 and 61. It is desirable, however, to provide means for intermittently energizing the light and audible signals. Any suitable means may be employed for 90 this purpose.

One form of mechanism for accomplishing this function is shown more or less diagrammatically in Fig. 3 in which a make and break device or switch 66 is shown. In 95 this diagrammatic showing, it is understood that the usual cutout or automatic switch devices will be supplied by those skilled in the art. Since the specific details of the wiring mechanism constitute no part of the present invention it is not thought necessary to further illustrate or describe the same. The switch comprises an arm 67 pivoted as at 68, and having one end adapted to close the circuit and its other end provided with means for engaging the cam wheel or roller 69. Preferably the lower end of the arm 67 is provided with the roller bearing 71 for engaging the periphery of the cam wheel 69. The cam wheel 69 is provided with one 100 or more projections 72 which may be arranged on the periphery of the wheel 69 in any suitable manner, to give any desired combination of signals. The wheel 69 is rotated thru a series of reducing gears 73 from a motor 74 which is operated from battery 35 in the usual manner.

The currents for operating the motor 74 and the switch device 66 may be traced as follows: The current for operating the motor 74 passes upwardly from the positive terminal 57 of the battery, thru the conductor 76, thru the field of the motor and from thence to the ground 77 and 78 back to the negative terminal 58 of the battery.

The current for operating the signals, passes from the positive terminal of the battery thru the conductor 79 to the ring 61 and from thence thru the conductor 65 to the lights and horn, returning thru con- 120 125 130

ductor 64, brush 62, conductor 83, and switch 66, when the same is closed and is grounded at 68.

In the operation of the device, the movement of the water past the casing 13 will cause rotation of the buoy, which in turn will operate the generator 34, for charging the battery 35.

The motor 74 will run continuously and the cam member 69 will cause an intermittent opening and closing of the switch 66, depending on the position of the projection 72, for energizing the two signals. While the signals are both shown as being in the same circuit, it is obvious that they may be placed in separate circuits and operated by independent switches.

In Fig. 4 is shown a modified form of the device in which the armature shaft 84 of the generator 85 is rigidly mounted on the casing 86 of the buoy and rotates therewith. The upper end of the armature shaft 84 is adapted to engage a recess in a closure 80, secured in the top of the casing 86.

The field 87 carried by the casing 88 is rotatably mounted on the armature shaft 84 by suitable bearings 89. The bearings 89 may be the usual ball bearing type with the co-operating races in the shaft and casing 88, whereby longitudinal movement of the casing along the shaft is prevented. Storage batteries 91 are attached to the casing 80 and will prevent said casing from rotating when the buoy is rotating.

In this form of the device the electric signal 92 is operated continuously from storage battery 91 thru conductors 93 in the usual manner.

In this form of the device the light signal 92 is carried by a skeleton frame 94 and is continuously energized from the batteries 91 thru the conductors 93. These extend upwardly thru closure 80 and thru tube or closed passage 95 for protecting the same.

If desired, the audible signals may be operated by mechanical means. As shown, preferably a plurality of bells 96 are carried by the support 97 of the skeleton frame 94. A suitable clapper 98 carried by a support 99 which is swivelled in projection 100 on the closure 80, is adapted to strike the bells as the same are rotated with the frame 94 during the rotation of the buoy.

In the operation of the audible signal, the weight of the clapper 98 will cause the same to hang perpendicularly in the path of the bells, and will strike the latter during their rotation.

While the invention is disclosed as being in the form of a signal device in which water

is the supporting medium and in which the electrical energy generated is employed for signal purposes, it is understood that the energy generated may be used for other than signaling purposes and that the supporting medium may be other than water since the same principle may be employed in aeronautics to indicate landing fields and the like.

It is to be understood that any combination of signals may be provided by changing the number or contour of the projections 72 on the cam 69. The form of the device shown in Fig. 1 will give two short signals comparatively close together with a relatively long period of time before repeating the same.

I claim as my invention—

1. In combination, a buoy comprising a casing, means for anchoring said buoy, a signal device, means for causing said buoy to rotate when water flows past the same, an electricity generating system, means for mounting said system within said casing whereby a portion of the same will be held by its own weight from rotating with said casing and the remaining portion will rotate with said casing for generating an electric current for energizing said device.

2. In combination, a buoy comprising a casing, means for anchoring said buoy, a signal device, means for causing said buoy to rotate when water flows past the same, mechanism within said casing for generating and storing electrical energy, means for mounting a portion of said mechanism so that it will be held by its own weight from rotating with said casing, and means for mounting another portion of said mechanism so that it will rotate with said casing for generating electrical energy for energizing said signal device.

3. In combination, a buoy comprising a casing, means for anchoring said buoy, a signal device, means on said casing for causing it to rotate when water flows past the same, a generator having rotating and non-rotating parts, a storage battery for receiving energy from said generator, means for supporting said battery within said casing so that the weight of the same will tend to prevent rotation of said non-rotating part and means for causing said rotating part to rotate with said casing for generating electrical energy for storing the same in said battery for operating said signal device.

In testimony whereof I affix my signature.

FRANCIS HOGG.
